To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying photograph, forming part thereof.

10 The leading feature of my design consists of ornaments or figures representing the Greek palmetto and composed of circles with fan-like branches shooting upwardly and outwardly from near the center of the circles 15 and projecting over the circles and fern-like branches curving outwardly from near the bottom of the circles and upwardly and inwardly on opposite sides of the circles and

forming inverted-heart-shaped ornaments surrounding the circles, as represented in the 20 accompanying photograph. These ornaments are arranged over the surface of the paper in horizontal rows, the ornaments in each alternate row being arranged vertically above each other. 25

The design is printed upon tinted paper of any desired color.

What I claim is—
